UNITED STATES PATENT OFFICE.

JOHN HAYS HAMMOND, JR., OF GLOUCESTER, MASSACHUSETTS.

RADIO TELEGRAPHY AND TELEPHONY.

1,320,685.

Specification of Letters Patent.

Patented Nov. 4, 1919.

Application filed May 29, 1912, Serial No. 700,425. Renewed December 28, 1918. Serial No. 139,419.

To all whom it may concern:

Be it known that I, JOHN HAYS HAMMOND, Jr., a citizen of the United States, residing at Gloucester, in the State of Massachusetts, have invented certain new and useful Improvements in Radio Telegraphy and Telephony, of which the following is a specification.

My invention relates to improvements in simultaneous radio telegraphy and telephony, and relates more particularly to systems in which one generator of electric waves can be used and telephone conversations can be carried on continuously, and telegraphic messages sent at the same time without interference.

In my system, a generator of continuous undamped electric waves is used, these waves being radiated from an antenna, and their amplitude controlled by a telephone transmitter in the usual way. The telegraph transmitting key does not stop the radiation, as is usual, but changes the value of the inductances in the oscillatory circuits of the transmitting station simultaneously, thereby keeping them in resonance and effecting the radiation of continuous undamped waves as before, but of a different wave length from those radiated when the telegraph key is not used.

At my receiving station I have two receiving circuits, one tuned to one of the transmitter wave lengths, the other tuned to the other transmitter wave length. One receiver circuit is arranged to receive only the telephone conversations; the other receiver circuit is arranged to receive both telephone conversations and telegraph signals.

Referring to the drawings,—

Figure 1 shows a transmitting station on my system.

Fig. 2 shows a receiving station on my system.

In Fig. 1, an arc O is supplied from a source of direct current M N, and produces undamped oscillatory currents in the circuit O C L, of a frequency determined by the values of the inductance L and the capacity C. Antenna circuit A L¹ T E is inductively coupled to L by coil L¹, and the amplitude of the radiated waves is effected by the telephone transmitter T so as to transmit telephone conversation by means of the radiated waves. The telegraph key K

makes simultaneous contacts at G and H, and thus simultaneously short-circuits parts of coils L and L¹, so that only the parts J and J¹ of the coils remain in circuit and so that the arc oscillatory circuit and the antenna circuit remain in tune, as they were before key K was closed. When key K is open, telephone conversations are carried on with radiated electric waves of a specific length, and when K is closed, telephone conversations can still be carried on with waves of a different length, and at the same time telegraph signals, due to the closing and opening of key K, can be transmitted.

Fig. 2 shows one form of receiving system constructed in accordance with this invention and comprising an open aerial circuit including an antenna B which leads through two branch circuits L² C¹ and L⁴ C² to a ground E. This open circuit is tuned to respond to the two high frequencies of the transmitting system. The branch circuits L² C¹ and L⁴ C² are coupled respectively to two closed resonant circuits L³ C³ and L⁵ C⁴ which are tuned to respond respectively to the two high frequencies of the transmitting system. Rectifier R supplies current from the circuit L³ C³ to one winding of the telephone receiver P¹. Rectifier R¹ supplies current from the circuit L⁵ C⁴ to the telephone P through the interrupter I; and R¹ also supplies current to the telephone winding P², which is on the same telephone receiver as P¹.

The circuits O C L and A L¹ T E of the transmitting station are in resonance with the circuit L³ C³ of the receiving station, and when the transmitting key K is open, telephone conversations only are transmitted and are received on one winding of the telephone P¹. The circuits O C J and A J¹ T E of the transmitting station are in resonance with the circuit L⁵ C⁴ of the receiving station, and when the key K is closed, telephone conversations may continue to be transmitted and will be received on the telephone winding P², which is connected with the same telephone as winding P¹. When key K is closed, telegraph signals will be received at telephone P, by means of the interrupter I, which will have a frequency within the limits of audibility.

Thus, the operator listening at P¹ P² will hear sounds originating at the telephone

transmitter T, regardless of the position of key K, and the operator listening at P will receive signals only when K is closed.

Instead of the oscillatory arc, some other 5 means of generating electric waves may be employed, and, in general, I do not confine myself to the specific means herein described for embodying my invention, but what I claim is:

10 1. In a system of simultaneous radio telegraphy and telephony, a transmitting station having closed and open oscillatory circuits, means for changing the frequency of said circuits and maintaining said circuits in resonance with each other, means for transmitting telephone messages with all wave frequencies, and means for transmitting telegraph signals at some wave frequencies, and a receiving station with a plurality of sets 20 of open and closed receiving circuits, each set of receiving circuits being in resonance with one of the wave frequencies of the transmitting station.

25 2. In a system of simultaneous radio telegraphy and telephony, a transmitting station having closed and open oscillatory circuits, means for changing the frequency of said circuits and maintaining said circuits in resonance with each other, means for transmitting telephone messages continuously, and means for transmitting telegraph messages intermittently.

30 3. In a system of simultaneous radio telegraphy and telephony, a transmitting station having closed and open oscillatory circuits, inductances in said oscillatory circuits, means for simultaneously changing the amount of said inductances, means for transmitting telephone messages with all values 35 of said inductances, and means for transmitting telegraph signals with some values of said inductances.

35 4. In an electric wave transmission system, a transmitting station having closed and open oscillatory circuits, inductances in said oscillatory circuits, means for simultaneously changing the value of said inductances, and concurrently sending telegraph signals, and means for transmitting 40 telephone messages with all values of the inductances.

50 5. A method of simultaneous radio telegraphy and telephony which consists in changing the wave frequency of the transmitting circuits and maintaining them in resonance impressing telephone vibrations and telegraph signals upon said circuits, continuously emitting electric waves and receiving them upon separately-tuned receiving circuits.

55 6. A method of selective radio transmission, which consists in continuously transmitting telephone messages and intermittently transmitting telegraph signals, changing 60 the wave length of the oscillatory cir-

cuits of the transmitting station and maintaining them in resonance continuously emitting electric waves and receiving them upon separately-tuned receiving circuits.

7. In a system of simultaneous radio telegraphy and telephony, a transmitting station having closed and open oscillatory circuits, means for changing the frequency of said circuits and maintaining said circuits in resonance with each other, means for transmitting telephone messages continuously, and means for transmitting telegraph messages intermittently, and a receiving station having means for receiving telephone messages at all frequencies of the transmitting station.

75 8. In a system of radio telegraphy and telephony, a source of energy, a plurality of coöperating tuned devices arranged to be energized from said source, means for varying the tuning of said devices at will, a telephone transmitter adapted to continuously impress waves corresponding to sound waves upon the waves of radiant energy emitted, and a telegraphing means intermittently operable for transmitting messages simultaneously with the waves impressed by said transmitter.

85 9. In a system of radio telegraphy and telephony, a source of energy, a plurality of coöperating tuned devices arranged to be energized from said source, means for varying the tuning of said devices at will, a telephone transmitter adapted to continuously impress waves corresponding to sound waves 90 upon the waves of radiant energy emitted, a telegraphing means intermittently operable for transmitting messages simultaneously with the waves impressed by said telephone transmitter, and separately tuned devices for receiving the respective telephone and telegraph messages.

100 10. A radio system for simultaneously transmitting telegraph and telephone messages, comprising means for transmitting a series of periodic radiant impulses having a predetermined frequency, means including a telegraphing device for changing the frequency of said impulses from time to time at the will of an operator to a second predetermined frequency to form telegraph messages, and means for impressing upon said impulses of both frequencies variations corresponding to sound waves to transmit telephone messages simultaneously with 105 said telegraph messages.

11. A radio system for simultaneously transmitting telegraph and telephone messages, comprising means for transmitting a series of periodic radiant impulses having 110 a predetermined frequency, means including a telegraphing device for changing the frequency of said impulses from time to time at the will of an operator to a second predetermined frequency to form telegraph 115 messages.

messages, means for impressing upon said impulses of both frequencies variations corresponding to sound waves to transmit telephone messages simultaneously with 5 said telegraph messages, and means for receiving said telegraph and telephone messages including two circuits tuned to respond to said frequencies respectively, telephonic receiving means controlled by 10 both of said circuits for receiving said telephone messages, and telephonic receiving means controlled by one only of said circuits for receiving said telegraph messages.

12. A radio system for simultaneously transmitting telegraph and telephone messages, comprising means for transmitting a series of periodic radiant impulses having a predetermined frequency, means including a telegraphing device for changing the 20 frequency of said impulses from time to time at the will of an operator to a second predetermined frequency to form telegraphic messages, means for impressing upon said impulses of both frequencies variations corresponding to sound waves to transmit telephone messages simultaneously with said telegraph messages, means for receiving said telegraph and telephone messages including two circuits tuned to respond to said frequencies respectively, telephonic receiving means controlled by both 25 of said circuits for receiving said telephone messages, telephonic receiving means controlled by one only of said circuits for receiving said telegraph messages, and means coöperating with said last-mentioned circuit for impressing audible variations upon the impulses received thereby.

13. A radio system for simultaneously transmitting telegraph and telephone messages, comprising an open aerial circuit, means for causing said circuit to emit periodic radiant impulses having a predetermined frequency, means including a telegraphic device for changing the frequency of said impulses to a second predetermined frequency from time to time at the will of an operator to transmit telegraph messages, and means for impressing upon said 45 impulses of both frequencies variations corresponding to sound waves to transmit telephonic messages simultaneously with said telegraphic messages.

14. In a radio system for simultaneously transmitting telegraph and telephone messages, the combination with an open aerial circuit including an inductance, of means including an inductance coöperating with said first-mentioned inductance for causing 55 said aerial circuit to emit a series of periodic impulses having a predetermined frequency, of means including a telegraphic device for simultaneously varying the effective lengths of said inductances to change 60 the frequency of said impulses to a second 65

predetermined frequency from time to time to transmit telegraphic messages, and a telephone transmitter arranged to impress variations corresponding to sound waves upon the impulses of both of said frequencies to transmit telephone messages simultaneously with said telegraphic messages. 70

15. In a radio system for transmitting telegraphic and telephonic messages, the combination with means for emitting periodic radiant impulses of a predetermined frequency, of means including a telegraph key operative to change the frequency of said impulses from time to time to a second frequency to transmit telegraphic messages, 80 and a telephone transmitter arranged to impress variations corresponding to sound waves upon the said impulses of both frequencies to transmit telephonic messages simultaneously with the said telegraphic 85 messages.

16. A radio system for simultaneously transmitting telegraphic and telephonic messages, comprising means for transmitting periodic radiant impulses having a predetermined frequency, of means including a telegraph key operative to change the frequency of said impulses from time to time to a second predetermined frequency to transmit telegraph messages, and a telephone transmitter arranged to impress upon said impulses of both frequencies variations corresponding to sound waves to transmit telephone messages simultaneously with said telegraph messages, and means 95 for receiving said telegraphic and telephonic messages including a receiving device responsive to both of said frequencies alternately and a device responsive to one only of said frequencies. 100

17. A system for simultaneously transmitting telegraphic and telephonic messages, comprising means for transmitting a series of periodic impulses having a predetermined frequency, means including a telegraphic device for changing the frequency of said impulses to a second predetermined frequency from time to time at the will of an operator to send a telegraphic message, and means for impressing upon said impulses of both frequencies variations corresponding to sound waves to send a telephonic message simultaneously with said telegraphic message. 110 115

18. A system for simultaneously transmitting telegraphic and telephonic messages, comprising means for transmitting a series of periodic impulses having a predetermined frequency, means including a telegraphic device for changing the frequency of said impulses to a second predetermined frequency 120 from time to time at the will of an operator to send a telegraphic message, means for impressing upon said impulses of both frequencies variations corresponding to sound waves to send a telephonic message simul- 125 130

- aneously with said telegraphic message, and means for simultaneously receiving said telegraphic and telephonic messages including a receiving device responsive to said impulses of both of said frequencies for receiving said telephonic message, and a device responsive only to said impulses of said second-mentioned frequency for receiving said telegraphic message. 60
- 5 19. A system for simultaneously transmitting telegraph and telephone messages, comprising means for transmitting a series of periodic impulses having a predetermined frequency, means including a telegraph key for changing the frequency of said impulses from time to time to a second frequency to send a telegraph message, a telephone transmitter arranged to modify said impulses of both of said frequencies in accordance with 15 20 sound waves to transmit a telephone message simultaneously with said telegraphic message, and means for simultaneously receiving both of said messages including a device responsive alternately to said impulses of both of said frequencies and a device responsive only to said impulses of said second-mentioned frequency. 25
20. A system for simultaneously transmitting telegraph and telephone messages, comprising means for transmitting a series of periodic impulses having a predetermined frequency, means including a telegraph key for changing the frequency of said impulses from time to time to a second frequency to 30 send a telegraphic message, a telephone transmitter arranged to modify said impulses of both of said frequencies in accordance with sound waves to transmit a telephone message simultaneously with said 35 telegraphic message, and means for simultaneously receiving both of said messages including a device responsive alternately to said impulses of both of said frequencies and a device responsive only to said impulses of said 40 second-mentioned frequency, said last-mentioned device including means for varying the effect of the received impulses of said second-mentioned frequency at a rate within audibility. 45
- 50 21. A method of simultaneous telegraphy and telephony, which consists in generating a series of periodic impulses having a predetermined frequency, changing the frequency of said impulses from time to time at the will of an operator to transmit a radio-telegraphic message, and impressing upon said impulses of all frequencies variations corre- 55
- sponding to sound waves to transmit a radio-telephonic message simultaneously with said telegraphic message. 60
22. A method of simultaneous telegraphy and telephony, which consists in generating a series of periodic impulses having a predetermined frequency, changing the frequency of said impulses from time to time at the will of an operator to transmit a radio-telegraphic message, impressing upon said impulses of all frequencies variations corresponding to sound waves to transmit a radio-telephonic message simultaneously with said telegraphic message, and selectively receiving said impulses of different frequencies causing a receiving device to respond to said impulses of each of said frequencies to receive said telephonic message, and controlling another receiving device as a result of the action of said impulses of one of said frequencies. 70
23. A method of simultaneous radio-telegraphy and telephony, which consists in generating a series of periodic radiant impulses having a predetermined frequency, changing the frequency of said impulses from time to time at the will of an operator to transmit a radio-telegraphic message, and impressing upon said impulses of all frequencies variations corresponding to sound waves to transmit a radio-telephonic message simultaneously with said telegraphic message. 80
24. A method of simultaneous radio-telegraphy and telephony, which consists in generating a series of periodic radiant impulses having a predetermined frequency, changing the frequency of said impulses from time to time at the will of an operator to transmit a radio-telegraphic message, impressing upon said impulses of all frequencies variations corresponding to sound waves to transmit a radio-telephonic message simultaneously with said telegraphic message, and selectively receiving said impulses of different frequencies causing a receiving device to respond to said impulses of each of said frequencies to receive said telephonic message and controlling another receiving device as a result of the action of said impulses of one of said frequencies. 90
